ALEXANDER NYMAN, OF SWISSVALE, AND FRANK CONRAD, OF PITTSBURGH, PENNSYLVANIA, ASSIGNORS TO WESTINGHOUSE ELECTRIC AND MANUFACTURING COMPANY, A CORPORATION OF PENNSYLVANIA.

POLYPHASE PLATE-CIRCUIT EXCITATION SYSTEM.

Application filed August 18, 1921. Serial No. 493,379.

Our invention relates to wireless transmission systems and particularly to oscillation-generator systems which are adapted to be excited by polyphase currents.

5 One object of our invention is to provide an oscillation-generator system employing thermionic tubes as oscillators which admits of the excitation of the tubes from polyphase alternating currents of commercial frequency.

10 Another object of our invention is to provide an alternating-current system of excitation for thermionic tubes wherein the ripple in the current supplied to the tubes is reduced very materially.

15 Still another object of our invention is to provide a scheme of transformer connections such that loads drawing direct-current components of energy may be supplied therefrom without resulting in the saturation of the iron cores of the transformer.

20 A further object of our invention is to provide an oscillation-generator system wherein modulated impulses of radio-frequency energy may be successively impressed upon an antenna circuit at such intervals as to cause substantially constant currents to traverse the antenna circuit.

25 Other objects of our invention will be apparent from the following description, when taken in connection with the accompanying drawing and claims.

30 Heretofore, one of the main difficulties encountered in employing polyphase currents to energize vacuum-tube oscillators has been to obtain an arrangement of transformer connections wherein the secondary windings will be traversed by currents which alternate in direction. As may readily be seen, since the oscillator tubes draw direct-current components of energy, a uni-directional field will be built up producing saturation of the magnetizable members of the transformer unless some provision is made to neutralize the magnetizing effect of such direct-current components.

35 We have found that, by employing transformer connections, as hereinafter described, the desired results may be obtained by employing only one tube per phase, whereas, heretofore, two oscillator tubes per phase have been required.

Our invention may be best understood by reference to the accompanying drawings, wherein;

55

Fig. 1 is a diagrammatic view of circuits and apparatus embodying our invention, wherein two Scott-connected transformers are employed;

Fig. 2 is a similar view, but shows a transformer having a simple star-connected secondary winding with connections for six phases, and

Fig. 3 is a similar view showing the secondary winding of the transformer connected in delta.

65

In the embodiment of our invention shown in Fig. 1, we have shown polyphase supply conductors 6, 7 and 8 connected to the Scott-connected primary windings 2 and 3 of a transformer 1, which is also provided with Scott-connected secondary windings 4 and 5, the winding 4 being connected to the middle point of the winding 5.

70

45 A plurality of evacuated electric devices 9, 11 and 12, which, for purposes of illustration, have been shown as thermionic tubes comprising plates 13, 14 and 15, grids 16, 17 and 18, and filaments 19, 21 and 22, respectively, are adapted to be energized by the secondary windings 4 and 5. The plates 13, 14 and 15 are connected to the three-phase terminals of the Scott-connected secondary windings by means of conductors 22, 23 and 24. The filaments are connected to a common point by means of conductors 25, 26 and 27 and are also connected, by means of a conductor 28, to a central point 29 in the winding 4. The conductor 28 may include a sustaining inductance 31 which serves to reduce the ripple of the direct currents supplied to the plate.

85

50 The filaments may be energized by any means well known to the art. In the drawings, we have shown one means of energization wherein the filaments are heated from a common source of energy 32.

95

55 As a matter of illustration, we have shown the evacuated tubes adapted to function as oscillation generators in such manner that substantially constant oscillations are caused to traverse an antenna circuit comprising an antenna 33, a tuning coil 34 and a ground lead 35.

100

A plate-filament circuit for the tube 9 comprises a conductor 36, which includes a stopping condenser 37 of relatively low impedance to high-frequency oscillations, a portion 38 of the tuning coil 34 and a return conductor 39 which is connected to the common terminal of the filaments. A plate-filament circuit for the vacuum tube 11 comprises a conductor 41, a stopping condenser 42, a conductor 43, the portion 38 of the tuning coil 34 and the return lead 39. A plate-filament circuit for the vacuum tube 12 comprises a conductor 44, a stopping condenser 45, the conductor 43, the portion 38 of the coupling coil 34 and the return conductor 39. It will be noted that the plate-filament circuits of the tubes are alike.

The grids 16, 17 and 18 have been shown as connected by conductors 46, 47 and 48, each of which includes a condenser 49 and a grid leak 51 for causing the grids to assume the proper negative potential, to such point on the tuning coil that a portion 52 is included in the grid-filament circuit of each tube.

In order to derive a three-phase supply from the secondary windings 4 and 5, the conductor 28 is connected to the transformer winding 4 at such point 29 that the number of turns included in the portion 53 between said point and the free terminal is just twice that included in the portion 54 between said point and the terminal which is connected to the mid-point of the winding 5.

Referring to Fig. 2, I have shown a transformer 55 which employs a six-phase star-connected secondary winding 56. It will be noted that, in this arrangement, six oscillator tubes are required. The filaments of each tube are connected to a common conductor 57 which is tapped to the neutral point 58 of the star connection. As in the previous figure, the common conductor 57 may also include a sustaining reactor 31. The general connections of the plate-filament and grid-filament circuits of each of the tubes are similar to those of Fig. 1.

Referring to Fig. 3, the arrangement here shown differs from that of the previous figures in that a delta-connected secondary winding 59 is employed and that the filaments are excited directly from the secondary winding, though a system of excitation, as shown in Figs. 1 and 2, is equally applicable to this system.

The plates 61, 62 and 63 of the tubes 64, 65 and 66 are connected by conductors 67, 68 and 69 through the windings 71, 72 and 73 to mid-points 74, 75 and 76 of the polyphase reactance device to the windings 77, 78 and 79, respectively. The filaments 81, 82 and 83 of the tubes 64, 65 and 66, respectively, are connected across portions 84, 85 and 86 of the windings 79, 77 and 78, respectively, one terminal of each filament being con-

nected to the delta terminal which is opposite the mid-point to which the corresponding plate is connected.

An artificial neutral point for the delta is obtained by means of three condensers 87, 70 opposite terminals of which are connected to the phase-terminals of the delta and to a common point 88. The plates and grids of the oscillator tubes are connected to the tuning coil 34, as in the previous figures. The 75 filament return conductor 39^a, however, instead of being connected directly to the filaments, is connected to the artificial neutral point 88 of the delta.

It will be noted that, in this system, as in 80 Fig. 1, it is necessary to employ only one tube per phase in order to neutralize the saturation effects of the direct-current components of energy.

In order to simplify our invention, in so 85 far as possible, we have omitted means for controlling or modulating the energy which is to be radiated from the antenna system. As will be readily understood by those skilled in the art, however, any of the well 90 known systems of modulation may be employed in our invention.

Referring to Fig. 1, the operation is as follows:

Assuming the anodes 13, 14 and 15 to be 95 come positive in the order in which they are mentioned, direct currents are first caused to flow through the portion 53 of the winding 4, then through portions 54 and 89 of the windings 4 and 5 and lastly through 100 portions 54 and 91 of the windings 4 and 5.

Assuming, as hereinbefore stated, that the number of turns included in portion 53 is twice that included in portion 54 and that the currents supplied to each tube are equal, 105 it will readily be seen that the magnetizing effect of the direct currents is completely nullified.

Assuming the constants of the plate-filament and grid-filament circuits of the oscillator tubes adjusted to the proper value, 110 high-frequency oscillations are generated, in a manner well known to those skilled in the art, during such periods as positive potentials are impressed upon their respective 115 anodes. While the oscillatory currents generated by each of the tubes are modulated at frequencies corresponding to those of the impressed electromotive forces, their combined effect in the antenna system is to produce currents of substantially constant amplitude and frequency.

Referring to Fig. 2, it will readily be seen that the magnetizing effect of the direct currents supplied to the tubes 92, 93 and 125 94 is neutralized by those currents which are supplied to the tubes 95, 96 and 97.

The thermionic tubes in the system shown in Fig. 2, as in the previous system, are operatively connected to the antenna circuit 130

and are adapted to generate radio-frequency currents during such periods as their plates have positive electromotive forces impressed thereon.

5 Referring to Fig. 3, it will be noted that the magnetizing effects of the direct-current impulses drawn by the tubes 64, 65 and 66 are neutralized, by reason of the derivation of potentials from the mid-point of one 10 winding to the opposite delta terminal. Thus, when the mid-tap 74 is positive with respect to the opposite delta terminal, equal and opposite currents flow in the two halves of the winding 77, while currents flow in the 15 windings 78 and 79 toward the point 74. When the mid-tap 75 is positive with respect to its opposite delta terminal, the currents in the two halves of the winding 78 are neutralized, while currents flow in the 20 windings 77 and 79 toward the point 75.

It will be noted that the current then flowing in the winding 79 is opposite in direction to the current therein when the mid-tap 74 was positive. When the mid-tap 76 is 25 positive with respect to its opposite delta terminal, the currents in the two halves of the winding 79 are neutralized, while currents flow in the windings 77 and 78 in a direction opposite to the flow when the 30 points 75 and 74, respectively, were positive. Thus, no leg of the transformer carries currents always in the same direction, and hence there is no tendency toward saturation.

35 While we have shown three embodiments of our invention for the purpose of illustrating and explaining the same, various modifications and adaptations will readily occur to those skilled in the art. We desire, therefore, that only such limitations shall be imposed upon our invention as are indicated in the appended claims.

We claim as our invention:

1. In a wireless transmission system, a 45 polyphase source of energy, a transformer having primary and secondary windings, the number of said primary windings corresponding to the number of phases and each primary winding being energized by 50 the corresponding phase of said source of energy, magnetizable cores for said windings, said secondary windings having pairs of circuit terminals, each pair constituting one phase of a polyphase source of energy, 55 a plurality of thermionic devices, conductors for connecting individual devices to individual phases, one of said conductors being common to said devices and including means for maintaining substantially constant currents therein, said pairs of circuit terminals including such portions of the secondary windings as are necessary to cause the magnetizing effects of the currents in each winding to be nullified, means including a radiating system associated with said thermionic 60

devices, and means for causing each thermionic device to function as an oscillation generator and to supply energy to said radiating system.

2. In an electrical system, a source of 70 polyphase energy, a transformer having primary and secondary windings, said primary windings being associated with said source of energy, said secondary windings having a Scott-connection, whereby polyphase currents may be drawn therefrom, magnetizable core members for said windings, a plurality of evacuated electric devices drawing direct-current components of energy, there being one device for each phase, said devices 75 having controlling electrodes and output electrodes, a conductor for connecting corresponding output electrodes to a central point in the secondary windings, and conductors for connecting the remaining output electrodes to the terminals of the Scott-connected 80 windings, said central point being so disposed as to cause the magnetic effects of the direct-current components of energy to be 85 nullified.

3. In an electrical system, a source of 90 polyphase energy, a transformer having primary and secondary windings, said primary windings being associated with said source of energy, said secondary windings being 95 connected in a Scott-connection, whereby polyphase currents may be drawn from the terminals thereof, magnetizable core members for said windings, a plurality of evacuated electric devices drawing direct-current components of energy, there being one device 100 for each phase of the Scott connection, said devices having controlling electrodes and output electrodes, a conductor for connecting corresponding output electrodes to a central 105 point in the secondary winding, said conductor including a reactance element tending to sustain the currents therein, and conductors for connecting the remaining output electrodes to the terminals of the Scott-connected 110 windings, said central point being so disposed as to cause the magnetic effects of the direct-current components of energy to be nullified.

4. In an electrical system, a source of 115 energy, a Scott-connected transformer operatively associated therewith, a plurality of evacuated electric devices drawing direct-current components of energy, said devices comprising input and output electrodes, a 120 conductor for connecting corresponding output electrodes to a central point in the secondary windings, said conductor including a sustaining inductor, conductors for connecting the remaining output electrodes to 125 the terminals of the Scott-connected windings, said central point being so disposed as to cause the magnetic effects of the direct-current components of energy to be nullified, and means including capacitance and in- 130

ductance elements associated with said input and output electrodes, whereby said devices may function as oscillation generators.

5. The combination with a transformer having two windings, one of said windings being connected to the mid-point of the other to form a three-phase Scott connection, said first-mentioned winding being provided with an intermediate tap providing a neutral terminal, and a plurality of similar translating devices carrying unidirectional currents, the terminals of said translating devices having a common polarity being connected to said neutral terminal, and the remaining terminals of said translating devices being connected to the respective three-phase terminals of said Scott connection.

6. The combination with a transformer having Scott-connected secondary windings, of three direct-current translating devices connected to the respective secondary phases, the number of turns of a secondary included between the said connections in each phase

respectively being such that the direct-current fluxes in each winding are neutralized. 25

7. The combination with a three-phase transformer having the end of at least one winding connected from one phase to another, said winding having a midtap, and one or more windings providing the third phase of said transformer, of means for providing a neutral terminal, and three unidirectional-current translating devices having their terminals of a common polarity connected to said neutral terminal, and their remaining terminals connected to said windings in such manner that equal components of current flow in opposite directions in the two halves of said winding having a midtap and the unidirectional magnetic fluxes in 30 all of the windings are neutralized. 35

In testimony whereof, we have hereunto subscribed our names this first day of August, 1921.

ALEXANDER NYMAN.
FRANK CONRAD.
